UNITED STATES PATENT OFFICE.

JAMES McKECHNIE, OF BARROW-IN-FURNESS, ENGLAND, ASSIGNOR TO VICKERS
LIMITED, OF WESTMINSTER, LONDON, ENGLAND.

CAR FOR AIRSHIPS.

1,339,570.

Specification of Letters Patent. Patented May 11, 1920.

Application filed April 25, 1919. Serial No. 292,720.

To all whom it may concern:

Be it known that I, Sir JAMES McKECHNIE, K. B. E., a subject of the King of Great Britain, residing at Naval Construction Works, Barrow-in-Furness, in the county of Lancaster, England, have invented certain new and useful Improvements in or Relating to Cars for Airships, of which the following is a specification.

10 This invention relates to cars for use on lighter-than-air craft such as airships or dirigible balloons (hereinafter termed airships).

According to one feature of the present invention the car is made of stream-line formation, *i. e.* approximately cigar shaped, and a short length of the nose or bow framework of the car is provided with transparent windows of glass or celluloid around its circumference, the extreme point of the nose of the car being also preferably cut off and, in the blunt end which is thus formed, a flat window, which may be circular and formed in two parts, is inserted. The 25 pointed nose of the stream-line car which would otherwise be unsuited for utilization by being made transparent in this manner is adapted for use as an observation station and an observer stationed therein can obtain an unobstructed view from the car in practically all directions.

Within the nose of the car may be provided the necessary instruments for navigating the air ship, *e. g.*, the prismatic compass and binnacle, and the navigating sights, and immediately abaft these may be placed the steering wheel and the seat for the navigating officer who is thus so positioned within the car that an unobstructed 40 view can, without movement, be readily obtained downwardly, forwardly and laterally.

According to another feature of the present invention and for the purpose of resisting shock on landing a pneumatic "bumping" or buffer bag or bags of any usual construction may be placed on the underside of the car framework and held in position by being inclosed within, or surrounded by a 50 watertight fabric covering, thus providing a water tight space or compartment (or spaces or compartments) of considerable area around the bag or bags. By these means a sufficient displacement is obtained 55 when landing on water to support the whole

car, while, at the same time, a buffer bag of smaller size than would otherwise be required can be employed. The weight of the buffer bag is thus reduced to a minimum while at the same time a bag of sufficient 60 strength to resist the increased internal air pressure encountered at high altitudes can be used.

In order that the said invention may be clearly understood and readily carried into 65 practice the same will now be described more fully with reference to the accompanying drawings, in which:—

Figure 1 is a longitudinal sectional elevation of the nose of the stream-line car. 70

Fig. 2 is a part sectional plan view of Fig. 1.

Fig. 3 is an elevation of the nose of the car looking in the direction of the arrow in Fig. 1, showing the windows in the forward 75 portion thereof.

Fig. 4 is an elevation of the center part of the car showing the buffer bag.

Fig. 5 is a section through the line Y—Y of Fig. 4.

Fig. 6 is an elevation of the buffer bag on an enlarged scale, and Fig. 7 is a section on a still larger scale, taken on the line X—X of Fig. 6.

A is the nose of the car, B, B are the windows disposed around its circumference, and C is the circular window in the blunt end of the nose of the car. D is the prismatic compass and binnacle, E designates the bomb and navigating sights, F is the 85 seat for the navigating officer or bombsighter, G is the steering wheel, H is the steering wheel pedestal and I is the cockpit. The seat F for the navigating officer is of the "tip-up" type and is attached to the 90 steering pedestal H, the steersman who stands in the cockpit I being thus situated immediately behind the navigating officer in such a position that a clear view of the prismatic compass is obtained by both. Navigating 95 orders can be transmitted by the officer to the coxswain by means of a suitably placed voice-pipe or a telephone (not shown).

As shown in the drawings the car, which 105 is approximately cigar-shaped and of stream-line form, is substantially polygonal in cross section and built up of longitudinal member J held in place by suitable transverse frames K, the structure being stiffened 110

by means of wire bracing L. The extreme point of the car is cut off to form the aforesaid flat circular window C and the first two sections M, N of the bow frame work are 5 adapted to carry the aforesaid circumferential windows B, B; both the circular window C at the nose and the windows B, B beneath the bombing sights being formed in two sliding parts c, c'. The remainder of 10 the car behind the transparent portion is suitably covered by fabric or other light material in order to reduce the weight to a minimum.

O is the buffer bag, which in the example 15 shown is of stream-line formation and composed of 5 ply fabric, and which is located within a covering of stout supporting canvas P stretched between two lower points Q, Q' of the car so that spaces or compartments p, p of large area are formed around the buffer bag O. At the upper edges of 20 the supporting canvas P are secured light canvas covering strips p', for the purpose of maintaining the covering watertight. 25 The covering is provided at its lower part with rubbing cords R which prevent damage to the covering P and which may be composed of coir cords fastened at front and rear to the covering P as shown at Fig. 4. 30 The buffer bag O is held in place by means of cords S which pass through flaps T secured to the buffer bag, the flaps t' being carried by a fabric strip t² secured to the top 35 of the buffer bag, which strip t² acts as a rubbing piece.

What I claim and desire to secure by Letters Patent of the United States is:—

1. A car for an airship, the nose of which 40 is employed as an observation station and is made transparent so that an observer stationed therein can obtain an unobstructed view in practically all directions, said car

being also provided with a pneumatic buffer bag which is inclosed within a waterproof covering, said covering being attached to the 45 car in such manner as to provide a watertight space or compartment around the lower side of said buffer bag.

2. A car for an airship, the nose of which is employed as an observation station and is 50 made transparent so that an observer stationed therein can obtain an unobstructed view in practically all directions, said car being also provided with pneumatic buffer means inclosed within a waterproof covering, the edges of said covering being attached to the car in such manner as to provide watertight spaces or compartments around the lower side of said buffer means.

3. A car for an air ship which is of 60 stream-line formation and in which a short length of the nose or bow framework is provided with transparent windows around its circumference, said car being also provided with pneumatic buffer means inclosed within a waterproof covering, said covering being attached to the car in such manner as to provide a watertight space or compartment around the lower side of said buffer means.

4. A car for an airship which is of 70 stream-line formation and in which a short length of the nose or bow framework is provided with transparent windows around its circumference, said car being also provided 75 with buffer means and with a waterproof covering inclosing said buffer means, said covering being attached to the car in such manner as to provide a water tight space or compartment of considerable area around the buffer means.

In testimony whereof I affix my signature.

JAMES McKECHNIE.
